A. R. P. JOHNSON

STENCILED INDICATING MEANS

Filed July 27, 1927

UNITED STATES PATENT OFFICE.

ALLAN ROLAND PYE JOHNSON, OF TORONTO, ONTARIO, CANADA.

STENCILED INDICATING MEANS.

Application filed July 27, 1927. Serial No. 208,847.

My invention relates to improvements in stenciled indicating means, and the object of the invention is to prevent the blurring of the stenciled outline so as to provide a clearly and sharply defined outline indication, which will be clearly visible when illuminated either by night or day, and yet will be totally obliterated when not illuminated so that any possibility of misunderstanding 10 the signal is absolutely avoided, and it consists essentially of the arrangement and construction of parts as hereinafter more particularly explained.

Fig. 1 represents a front elevation of any 15 suitable form of indication casing showing my stenciled means incorporated therein partially broken away to exhibit the construction thereof.

Figs. 2, 3 and 4 are perspective details of 20 the sheets forming my indicating means separated apart.

Fig. 5 is a sectional view through the assembled sheets showing a light source and the general direction of the rays passing 25 therefrom.

In the drawing like characters of reference indicate corresponding parts in each figure.

1 indicates an indicator casing provided with the usual indicator openings 2, 3 and 4. 30 5, 6 and 7 are sheets of celluloid or other suitable material which when assembled are formed to fit behind the orifices 2, 3 and 4 as indicated in Figure 1.

The sheet 5 is semi-opaque and orange in 35 colour. The sheet 6 is provided with stenciled openings 6^x, 7^x and 8^x and is black and is superimposed upon the sheet 5 so that the orange celluloid appears through the openings 6^x, 7^x and 8^x. The sheet 7 is purple in 40 colour and semi-opaque and is superimposed over the sheet 6 so as to extend over the openings 6^x, 7^x and 8^x. When so arranged the sheets are placed behind the openings 2, 3 and 4 and are held by the casing in such 45 position. The semi-opaque celluloid sheet 5 being placed underneath or inside of the sheet 6 permits the stenciled design of arrow or hand to show distinctly whether or not the celluloid is warped.

50 By placing the purple sheet of celluloid over the stenciled sheet the outline of the indication, whether hand or arrow, when not illuminated is rendered indistinct or prac-

tically obliterated, and yet will permit of the design to show distinctly when lit up 55 either in the day time or at night. The purple celluloid also aids in detracting the light rays of the sun, etc., giving the stenciled openings a deep black background, providing a maximum contrast to the orange 60 colour permitting it to show up clearly, and at the same time providing a colour which contrasts with the colour of the tail light.

In my construction as before stated the colour sheet 5 is placed on the inside of the 65 stenciled sheet 6 and therefore if there is any tendency for the stenciled sheet to warp at the edge of the stenciled opening it will not affect the clearness and sharpness of the outline of the signal indication.

70 Further by placing the purple sheet 7 over the sheet 6 not only are the stenciled edges of the sheet 6 held firmly in place, but the purple of the sheet 7 serves to deepen the black background effect of the sheet 6 when the indicator is illuminated, and when it is not illuminated serves to absolutely hide the outline of the indication by toning the colour of the sheet 5 into the black background formed by the sheet 6.

75 By placing the purple sheet over the orange sheet and the black stenciled sheet, the blackness of the background is deepened in tone and the light rays passing through the orange sheet are modified to produce the 80 colour which has been found in practice to most readily strike the eye and therefore giving the sign a maximum visibility.

85 From this description it will be seen that I have devised a very simple device which will provide a clear, vivid sharply defined outline to the indicating signal, which will always be clearly visible when illuminated, and which when not illuminated will be rendered invisible to the driver of any other 90 car in its proximity.

95 What I claim as my invention is:—

100 1. A stenciled indicating means comprising a composite sheet consisting of an inner sheet of suitably coloured semi-opaque material, an intermediate stenciled sheet of a contrasting dark shade, and an outer sheet of a colour tending to tone or merge the colour of the inner sheet when unilluminated into that of the intermediate or background sheet.

2. A stenciled indicating means comprising an inner semi-opaque sheet orange in colour, an intermediate black stenciled sheet, and an outer transparent purple sheet superimposed one upon the other.

3. An indicator adapted to be illuminated and comprising an inner transparent suitably colored sheet, means permitting light

rays to pass through a portion of the sheet and for obstructing the light rays through the remainder of the sheet to form an opaque background and a sheet overlying the aforesaid sheet and of a color tending to merge or tone the color of the transparent portion into the opaque background. 10

ALLAN ROLAND PYE JOHNSON.
